HASP CONSTRUCTION

Application filed February 11, 1927. Serial No. 167,396.

The present invention relates to hasp construction.

The present invention is useful in connection with the sliding doors of railway house cars and will be described with particular reference thereto. In locking the sliding doors of railway house cars, it is common practice to provide a hasp upon the sliding door adapted to cooperate with a staple secured to the door jamb. It is common practice to rely upon the staple and hasp in cooperation with a bolt or the like not only to lock the sliding door but also to hold the door against vibration in service. The door jamb and the rear edge angle of the door limit movement of the door in a closing direction in the event that the door is of proper width. When the door has a width less than the proper dimension, the rear edge angle will ordinarily limit movement of the door in a closing direction. In order to hold the door against rearward or opening movement, the portion of the hasp defining the forward end of the slot in said hasp is relied upon to engage the staple to prevent such rearward or opening movement of the door. In certain instances, particularly where repairs have been made, the hasp and the staple are not properly placed relative to one another, and it is sometimes impossible to dispose the hasp upon the staple.

An object of the present invention is to provide a hasp construction having a pair of slots which may be used alternatively to suit varying conditions.

A further object is to provide a hasp construction which is cheap to construct, simple to install and which will operate effectively even in the case of considerable variation from the proper dimensions of the door and doorway with which it cooperates.

Further objects will appear as the description proceeds.

Referring to the drawings—

Figure 1 is a fragmentary view of part of a side of a car having an embodiment of the present invention applied thereto;

Figure 2 is a top plan view of the locking structure shown in Figure 1, part of the door and door jamb being shown in section;

Figure 3 is a view similar to Figure 1 but showing the hasp turned through an angle of 90 degrees; and

Figure 4 is a sectional view taken along the plane indicated by the arrows 4—4 of Figure 3, showing the L-shaped cross-section of a hasp employed in the practice of the present invention.

The numeral 1 indicates a door jamb and the numeral 2 indicates a sliding door. Mounted upon the door jamb 1 is the locking plate 3, which provides a support for a reciprocating bolt 4 having the shank 4^a, the particular bolt illustrated being provided with a slot 5 for receiving an outstanding headed pin 6. Said plate 3 also provides a staple or keeper lug 7 and a sealing lug 8.

Mounted upon the sliding door 2 is the usual metal strap 9, which provides a support for the hasp fastener 10. The hasp fastener 10 has a goose-neck portion 11 of novel conformation, the end portion of said goose-neck portion being disposed within an aperture 12 in said strap 9. The extremity of the goose-neck 11 is provided with the shoulder 13 which underlies the material of the strap 9 when the hasp fastener is in place. Said hasp fastener and strap are secured to the door 2 by means of bolts, one of which is indicated by the numeral 14. The forward edge of the sliding door 2 may be provided with the Z-bar 15 which with the forward extremity of the strap 9 may be held in position by means of the bolt 16. The Z-bar 15 provides a forwardly extending lip 17 adapted to fit within a pocket 18 formed within a metal member 19 secured to the door jamb.

Disposed upon the goose-neck 11 is the hasp 20, which as best shown in Figure 4, is of angular cross section. The hasp 20 is provided with the aperture 21 for receiving the goose-neck 11. Said goose-neck 11 has a portion 22 extending at substantially right angles to the plane of the strap 9 and has another portion 23 extending substantially parallel to the plane of the strap 9.

As noted above, the hasp 20 is L-shaped in cross section (see Figure 4). One leg, indicated by the numeral 24, has an aperture 25 of a length to more or less closely receive the

staple or keeper lug 7, sufficient tolerance being provided to meet operating conditions. The aperture 25 will be so located in the hasp 20 that with the door 2 in home position and 5 the locking plate 3 in proper position, said aperture 25 and staple or keeper lug 7 will register, as shown in Figure 1.

The other leg 26 of the hasp 20 is provided with a slot 27, the outer extremity of which, 10 indicated by the numeral 28, is disposed outwardly of the outer extremity of the slot 25 for purposes which will be referred to hereinafter. The slot 27 is preferably longer than the slot 25, the inner extremity 29 of said 15 slot being closer to the goose-neck 11 than is the inner extremity of the slot 25. With the slot 25 registering with the staple or keeper lug 7 as shown in Figure 1, the locking bolt 4 extends through the slot 27.

20 In case it is not possible to move the door 2 to its home position, the hasp 20 may be moved to a position 90 degrees from that shown in Figure 1 to occupy the position illustrated in Figure 3 with the leg 26 of the 25 hasp 20 lying parallel with the side of the car. Inasmuch as the outer extremity 28 of the slot 27 is disposed at a greater distance from the goose-neck 11 than is the outer extremity of the slot 25, the staple or keeper 30 lug 7 may be disposed within said slot, even if it is not possible to move the door 2 to home position. Under these conditions, not only will the door 2 be locked but sliding movement of the door in service in an opening direction will be prevented by the extremity 28 of the slot 27. By reason of the fact that the 35 inner extremity 29 of the slot 27 is closer to the goose-neck 11 than is the inner extremity of the slot 25, variations from the proper 40 positioning of the keeper lug toward the right as the parts are viewed in Figure 4 may be compensated for.

Though a preferred embodiment of the present invention has been described in detail, many modifications will occur to those skilled in the art. It is intended to cover all such modifications that fall within the scope of the appended claims.

We claim:

50 1. In combination, a staple, and a hasp for cooperation with said staple, said hasp being L-shaped in cross section transversely of said hasp and having a staple receiving slot in each of the legs of said L-shaped cross section, one of said slots being of a length to closely receive said staple, the other of said slots being of greater length.

60 2. In combination, a staple, and a hasp for cooperation with said staple, said hasp being L-shaped in cross section transversely of said hasp, each of the legs of said L-shaped cross section being provided with a staple receiving slot, the outer extremity of one of said staple 65 receiving slots being disposed nearer to the

swinging extremity of said hasp than is the outer extremity of the other of said slots.

3. In combination, a staple, and a hasp for cooperation with said staple, said hasp being L-shaped in cross section transversely of said hasp, each of the legs of said hasp being provided with a slot for receiving said staple, the outer extremity of one of said slots being disposed nearer to the outer swinging end of said hasp than is the outer extremity of the other of said slots, the inner extremity of said first mentioned slot being nearer to the inner end of said hasp than is the inner extremity of said other of said slots.

4. In combination, a staple, a hasp for said staple, and means for supporting said hasp, said hasp having two flanges disposed in substantially right angular relation to one another, said supporting means having a holding portion for permitting the disposition of said hasp with either of said flanges in a plane at right angles to the plane of said staple, each of said flanges being provided with a slot for receiving said staple.

5. In combination, a staple, a hasp for said staple, and means for supporting said hasp, said hasp having two flanges disposed in substantially right angular relation to one another, said supporting means having a holding portion for permitting the disposition of said hasp with either of said flanges in a plane at right angles to the plane of said staple, each of said flanges being provided with a slot for receiving said staple, one of said slots being of a length to closely receive said staple, the other of said slots having a length greater than the corresponding dimension of said staple.

6. In combination, a staple, a hasp for said staple, and means for supporting said hasp, said hasp having two flanges disposed in substantially right angular relation to one another, said supporting means having a holding portion for permitting the disposition of said hasp with either of said flanges in a plane at right angles to the plane of said staple, each of said flanges being provided with a slot for receiving said staple, one of said slots having its outer extremity disposed at a greater distance from said supporting means than is the corresponding extremity of the other of said slots.

7. In combination, a staple, a hasp for said staple, said hasp having a pair of flanges disposed in right angular relationship with one another, a hasp fastener, said hasp fastener having a neck for supporting said hasp and permitting a swinging movement thereof in a plane parallel to the plane of said staple and a turning movement thereof to permit the disposition of each of said flanges in right angular relationship with the plane of said staple.

8. In combination, a staple, a hasp for said staple, said hasp having a pair of flanges disposed in right angular relationship with one

another, a hasp fastener, said hasp fastener having a neck for supporting said hasp and permitting a swinging movement thereof in a plane parallel to the plane of said staple and a 5 turning movement thereof to permit the disposition of each of said flanges in right angular relationship with the plane of said staple, each of said flanges being provided with a slot for receiving said staple, the outer extremity 10 of one of said slots being disposed at a greater distance from said neck portion than is the outer extremity of the other of said slots.

9. In combination, a hasp for cooperation with a staple, means for swingingly supporting said hasp while permitting the rotation thereof through an angle of ninety degrees about its longitudinal axis, said hasp being L-shaped in cross section transversely of said hasp and having a staple receiving slot in 20 each of the legs of said L-shaped cross section, the outer extremities of said slots in said two legs being disposed at different distances from the axis of swing of said hasp.

Signed at Chicago, Illinois, this 20th day 25 of January, 1927.
